Primary Examiner — Kevin Rudzinski*Assistant Examiner* — Paul Bohannon(74) *Attorney, Agent, or Firm* — Andrus Intellectual Property Law, LLP(57) **CLAIM**

The ornamental design for a pivotal conference room table, as shown and described.

DESCRIPTION

FIG. 1 is a front perspective view of the pivotal conference room table showing our new design;

FIG. 2 is a top plane view thereof;

FIG. 3 is a bottom plane view thereof;

FIG. 4 is a front side elevation view thereof;

FIG. 5 is a back side elevation view thereof;

FIG. 6 is a left side elevation view thereof;

FIG. 7 is a right side elevation view thereof;

FIG. 8 is a top plane view thereof showing a pivoted position; and,

FIG. 9 is a top plane view thereof showing an alternate pivoted position.

(Continued)

The broken lines represent portions of the pivotal conference room table that are shown for purposes of illustrating environment and form no part of the claimed design.

1 Claim, 7 Drawing Sheets
